CLAIM

The ornamental design for a set of components for a phone case, as shown and described.

DESCRIPTION

FIG. 1 is a front, left-side, and top perspective view of a set of components for a phone case showing my new design; FIG. 2 is a rear, right-side, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, left-side, and top perspective view thereof showing a component in a folded state;

FIG. 10 is a rear, right-side, and bottom perspective view thereof showing a component in a folded state; and,

FIG. 11 is an enlarged detail view of area 11 in FIG. 2.

The dot-dash broken lines in FIGS. 2 and 11 form no part of the claimed design and designate a portion of the claimed design that is shown on an enlarged scale in FIG. 11. The dashed broken lines throughout the drawing figures form no part of the claimed design and depict portions of the set of components for a phone case that form no part of the claimed design.
